CLAIM

The ornamental design for wrist-borne exercise display device, as illustrated and described.

DESCRIPTION

FIG. 1 is a front perspective view of wrist-borne exercise display device showing my new design with one display activated;

FIG. 2 is a front perspective view thereof with another display activated;

FIG. 3 is a front elevational view of FIG. 1;

FIG. 4 is a front elevational view of FIG. 2;

FIG. 5 is a right side elevational view thereof;

FIG. 6 is a rear elevational view thereof; and,

FIG. 7 is a left side elevational view thereof.

The characteristic feature of my new design resides in the particular display screens best shown by FIGS. 1 and 2, the case and band being conventional.
